UNITED STATES PATENT OFFICE.

CHARLES SICKERT, OF DAVENPORT, IOWA.

GAS GENERATOR AND BURNER.

1,206,931.

Specification of Letters Patent.

Patented Dec. 5, 1916.

Application filed June 27, 1916. Serial No. 106,137.

To all whom it may concern:

Be it known that I, CHARLES SICKERT, a citizen of the United States, residing at Davenport, in the county of Scott and State 5 of Iowa, have invented certain new and useful Improvements in Gas Generators and Burners, of which the following is a specification.

The primary object of this invention is the 10 production of a simple and efficient device for generating gas as distinguished from vapor, from kerosene, and utilizing the gas generated for furnishing the heat to gasify the kerosene, to start the burner, and for 15 such other purposes as may be desired, the burner which generates the gas acting as a heater which may be used in stoves, furnaces or elsewhere.

In order to more fully describe my invention, reference will be had to the accompanying drawings wherein:

Figure 1, represents in side elevation a two-unit apparatus embodying my invention; Fig. 2, a top plan view thereof, showing the connection to the storage tank, and, 25 Fig. 3, an enlarged section on line 3^x—3^x, Fig. 2.

In the accompanying drawings 1 and 2, represent two burner units mounted upon a 30 gas settling tank 3, which latter is connected through pipe 4, and valve 4', to a gas storage tank 5, later more particularly described. Each of the burner units comprises, among 35 other parts, a casting 6, having a central opening 7 passing vertically through it, a chamber 8 surrounding said opening, and an annular flange 9 forming a baffle. Chamber 8 constitutes the superheating chamber, as will presently more fully appear, and is in 40 communication through pipe 10 with the interior of the settling tank 3, said pipe also constituting a support for the generator. Casting 6 has an annular stepped shoulder 45 11 upon which rests a perforated thin metal ring 12, and resting upon the top of this ring is a removable cast iron cap 13, said ring and cap forming a chamber inclosing the top of casting 6.

Each burner is provided with a pipe coil 50 14 surrounding the burner ring 12 and lying in the annular space formed by the baffle flange 9. This pipe is in communication at one end with chamber 8 through elbow 15. The other end of pipe 14 is communicated 55 with a source of kerosene under pressure, and is provided with a valve 16 for control-

ling the flow of the kerosene to the coil. Directly below the opening 7 is located a nozzle 17 which is in communication through a valve 18 with the settling tank 3. This valve 60 has an elongated operating stem 19 which extends far enough to one side of the burner to be readily accessible. Rods 20 assist the pipe 10 in supporting casting 6.

The operation is as follows: If the burner 65 has never before been used, the initial heat to start gasifying the oil in pipe 14 may be supplied from some exterior source, for example, as from a pan of alcohol placed under the casting 6, or it may be supplied 70 from the storage tank 5 previously charged for this purpose. Assuming that the burner is started from gas in the tank 5, the first operation is to open valves 4' and 18 and permit gas to issue from nozzle 17, whence 75 it passes through chamber covered by cap 13, thence through the perforations in ring 12, where it is lighted and burns. Valve 16 is then opened to deliver the kerosene to the pipe coil 14. The flame from the burner 80 will impinge on the pipe coil thus heating it to such a degree as to gasify the oil and vapor in the coil. This gas then passes into the superheating chamber 8 when it is further heated and passes thence to the set- 85 tling tank 3 through pipe 10. The primary purpose of this tank is to allow for the settling of any foreign matter which may have been brought through pipe coil 14, 90 thus preventing the stoppage of the jet nozzle 17. The surplus gas from the tank 3 is conveyed to the storage tank 5 from which it may be used for illumination or other purposes.

The baffle 9 deflects the flame and heat 95 from the burner back upon the pipe coil which is subjected thereby to intense heat. As a matter of fact, the whole casting 6 becomes very highly heated and the arrangement is such that this generator really 100 generates gas as distinguished from vapor; that is, gas which may be stored for a considerable length of time without condensing or returning to the liquid state. Again, the gas generated by my burner being capable 105 of retention for long periods in the tank 5, may at any time be used for starting the generator, thus avoiding the necessity of having to use some extraneous heating medium, as is the common practice.

This device will actually convert coal oil 110 or kerosene into gas which may be stored

for long periods, and this is not possible with other gas burners and generators of this general type, as far as I am aware.

While I have shown and described one specific embodiment of my invention, it will be understood that the same may be modified without departing from the spirit thereof.

What I claim is:

- 10 1. A gas generator and burner, comprising a casing having a central vertical opening passing through it, and a superheating chamber surrounding said opening, an annular perforated ring surrounding said casing, a cap fitting over said ring, a pipe coil around said casing exterior to said perforated ring, and opening into said superheating chamber, an annular baffle on the opposite side of said coil from said casing, a nozzle arranged to direct a jet of gas into the central passage through said casing, and means forming a connection for conducting gas from said superheating chamber to said nozzle.
- 15 2. A gas generator and burner, comprising a casing forming a superheating chamber, a pipe coil around said casing and opening into the superheating chamber thereof,
- 20
- 25

a burner between said casing and said coil, an annular baffle on the opposite side of said coil from said casing, a gas receiver, a pipe leading from said superheating chamber to said receiver, a gas nozzle arranged to deliver gas past the exterior of said casing to said burner, and means to deliver gas from said receiver to said nozzle.

3. A gas generator and burner, comprising a casing forming a superheating chamber, a pipe coil around said casing and opening into the superheating chamber thereof, a burner between said casing and said coil, an annular baffle on the opposite side of said coil from said casing, a pipe leading from said superheating chamber, a gas nozzle arranged to deliver gas past the exterior of said casing to said burner, and means to deliver gas from said pipe leading from the superheating chamber to said nozzle.

In testimony whereof I affix my signature in the presence of two witnesses.

CHARLES SICKERT.
